FABRIC TENSIONING CLAMP

Filed May 11, 1929

UNITED STATES PATENT OFFICE

ALEXANDER C. PARLINI, OF WOODSIDE, NEW YORK, ASSIGNOR TO GOTHAM SILK HOSIERY COMPANY, INC., OF NEW YORK, N. Y., A CORPORATION OF DELAWARE.

FABRIC-TENSIONING CLAMP

Application filed May 11, 1929. Serial No. 362,199.

This invention relates to fabric tensioning clamps for hosiery knitting machines and has for its object the provision of a simple and efficient clamp attachment for maintaining 5 the leg portion of a full fashioned knitted stocking under tension while the foot portion is being knitted on the so-called "footer" knitting machine.

In forming full fashioned stockings the 10 leg fabric is usually knit first on what is known as the "legger machine". Thereafter the fabric is transferred to the so-called "footer" machine for knitting the foot portion. In knitting the foot portion onto the 15 leg fabric it is necessary to keep the fabric under a certain tension as the knitting progresses. In the art heretofore practised this was commonly accomplished by the use of a series of hooks fastened into the fabric and 20 exerting a pull so as to tension the fabric while the same was knitted. On account of the sharp hooks engaging the delicate fabric frequent damage occurred in either breaking the threads or injuring the same so that 25 the knit fabric was injured and a defective stocking resulted therefrom.

It is the object of my invention to replace the so-called footer hooks by my improved fabric tensioning clamp, whereby the fabric 30 is engaged under uniform pressure without any injury to the fabric itself. My improved clamp attachment is moreover so constructed so as to be readily applied and the fabric can be quickly adjusted thereon.

35 A further object of my invention includes the provision of means for eliminating the spreading of stitches in the knitted fabric and in particular in the instep portion of full fashioned hosiery.

40 Other objects will appear hereinafter and I obtain these objects by the mechanism illustrated in the accompanying drawing in which—

Fig. 1 is a plan view of my improved fabric tensioning clamp showing also in broken lines the position of the knitted fabric;

Fig. 2 is an end view of the clamp;

Fig. 3 is a section taken on the line 3—3 of Fig. 1, and

Fig. 4 is a section taken on the line 4—4

of Fig. 1, viewed in the direction of the arrows.

Like reference numerals refer to the same parts wherever they occur.

In a preferred form of construction my 55 improved fabric tensioning clamp comprises a base plate 10, of suitable dimensions, provided with tab hooks 11 for engaging the heel tabs on the knitted fabric. The tab hooks are fastened onto the base plate near 60 the extremities thereof by suitable means, such as screws 12. Intermediate of the tab hooks on the base plate, there are mounted a pivot stud 13 and a latch stud 20 suitably spaced. The pivot stud engages clamp bar 14 65 by means of a pivot pin 15 so as to permit the clamp bar to swing freely upon the pivot 15. The opposite end of the clamp bar 14 engages the latch stud 20 as shown in Figs. 1 and 4. A sleeve 16 fits loosely on the clamp 70 bar 14 and is held on the bar by ears 17. This sleeve carries fastened thereon an eccentric sleeve 18 which is mounted immediately above the fabric holding plate 21. Plate 21 is fastened to the base plate 10 and the eccentric member and the fabric holding plate 75 constitute the clamping means for holding the fabric. Near one end of the sleeve 16 there is fastened a hand operated lever 19, whereby sleeve 16 is rotated so as to bring 80 the eccentric clamp 18 to bear upon fabric 25 for holding the same as is shown in Fig. 3.

From the construction of the clamp herein disclosed it will be apparent that the clamping members rigidly and securely engage the 85 fabric to hold the same at desired positions and the clamp is readily engaged or released by the finger lever 19, while the bar engages the latch stud 20. It is further also apparent that plate 21 constitutes one jaw member and 90 the rotatively held eccentric sleeve 18, the other, and that the latter jaw member positively closes upon the former when the sleeve member is rotated as by turning the lever 19.

The fabric is taken up by the usual take up 95 roll 22, which is properly adjusted and timed so as to tension the fabric during the knitting operation. The clamp device is simple in construction, positive in its action and operates on the fabric without injury thereto. 100

It is obvious to those versed in the art that various minor details of construction will suggest themselves and I have illustrated a specific form of my invention, as an example, whereby to successfully operate in avoiding injury to the knit fabric as outlined above.

Having now described my invention what I claim as new and useful and desire to secure by Letters Patent is:

- 10 1. In a fabric tensioning clamp for footer attachments, a base plate having studs mounted thereon in spaced relation, a bar swingably held on one of said studs and engaging the other of said studs at a definite distance from the base plate, an eccentric sleeve on said bar and means spaced apart from the sleeve to rotate said sleeve about said bar.
- 15 2. In a fabric tensioning clamp for footer attachments, a base plate having studs mounted thereon in spaced relation, a bar swingably held on one of said studs and engaging the other of said studs at a definite distance from the base plate, a sleeve loosely held on said bar and a second sleeve eccentrically fixed on said first named sleeve and means spaced apart from the sleeve to rotate said sleeves.
- 20 3. A fabric tensioning clamp for footer attachments, comprising a base plate, having tab hooks, studs spaced apart on said base plate, a clamp bar mounted upon one of said studs and engaging the other of said studs, a bar sleeve on said bar, an eccentric sleeve on said bar sleeve, and means on said bar sleeve to rotate said bar sleeve on the bar.
- 25

In testimony whereof I have hereunto set my hand on this 8th day of May, A. D. 1929.

ALEXANDER C. PARLINI.
